EXHAUST PLANT FOR SPINNING MACHINES
FOR CATCHING AND REMOVING THREAD
ENDS

Heinrich Thoma, Zurich, Switzerland

Application October 13, 1941, Serial No. 414,796
In Germany October 17, 1940

2 Claims. (Cl. 57—56)

The present invention relates to a suction device for collecting and removing broken ends in spinning and the like machines and has for its object to provide a device of this character that will function continuously without clogging of the suction passages by the broken ends.

Devices of this character, as heretofore constructed, have been open to the objection that they become clogged after operation for a considerable period. Such clogging is due primarily to the formation of eddy currents in the suction passages and the fact that the cross sectional areas of the passages are not properly proportioned so as to insure a uniform distribution of the suction draft over the entire arrangement of passages.

According to the present invention, the difficulties encountered in the operation of prior devices are overcome by constructing the main collecting conduit and the individual suction heads of varying cross section throughout, always increasing in area in the direction of movement of the broken ends through the suction heads and main collecting conduit toward the suction source. By reason of the above described construction, the device will operate continuously, without clogging, by reason of the uniform flow of broken ends in the suction stream and the absence of eddy currents that would otherwise tend to deposit the broken ends as a mass at any point in the system where a back eddy exists.

The above and other advantageous features of the invention will hereinafter more fully appear from the following description, considered in connection with the accompanying drawing, in which

Fig. 1 is a longitudinal sectional view of an individual suction head embodying the invention,

Fig. 2 is a transverse section along the line II—II of Fig. 1,

Fig. 3 is a plan view of an assembled collecting conduit and suction heads,

Fig. 4 is a transverse section through the conduit, along the line IV—IV of Fig. 3, and

Fig. 5 is a diagrammatic view, partially in section, showing the installation of a device embodying the invention in association with a spinning machine.

Referring first to Fig. 5, there is shown a portion of a spinning frame providing spools 1 from which roving 2 is drawn by rolls 3 for winding on spindles 4 in a manner usual with the operation of spinning machinery. In accordance with the present invention, there is associated

5 with the spinning frame a conduit 5 extending longitudinally of the machine, this conduit being readily built into the existing machine below the creel or spool stand 6. The conduit 5 preferably is of rectangular cross section, as shown in Fig. 4, with its right hand end closed, as viewed in Fig. 3, and its opposite open end connected to a suitable suction source, as indicated at 7. It is to be noted that the conduit 5 is tapering in form, as viewed in plan, so that the cross sectional area thereof increases from its closed end toward the suction source.

10 The conduit 5 provides series of suction heads 8 projecting from opposite sides thereof, with the several heads of each series extending along the machine transversely to the rovings 2, as they move downwardly from the drawing rolls 3 to the spindles 4. As best shown in Fig. 1, each suction head 8 provides a series of individual suction holes 9 so spaced along the head so as to substantially coincide with the individual rovings 2. It is to be noted that while each suction head 8 is of generally circular cross section, as shown in Fig. 2, each head is tapered longitudinally so that the head is of varying cross section throughout, increasing in area from the closed end of the head to its connection with the main conduit 5. Preferably, the suction holes 9 increase in size from the suction end to the closed end, as shown in Fig. 1, in inverse relation to the taper of the head itself.

15 When the spinning machine is in operation and the main conduit 5 is connected to a source of suction, it is obvious from a consideration of Figs. 1 and 5 that whenever a roving 2 breaks, the broken end will be sucked into the corresponding suction hole 9, and that all broken rovings will travel from the heads into the conduit toward the suction source, as indicated by the arrows in Fig. 3. By reason of the varying cross section of the main collecting conduit 5 and individual suction heads 8, always increasing in the direction of movement of the broken ends toward the suction source, there will be no tendency for the broken ends to build up at any point and clog the suction passages. The fact that the individual openings 9 of each head 8 increase in size away from the suction source, insures that sufficient air flow will be obtained in these openings further removed from the suction source than the openings adjacent the connection of each head with the main conduit 5.

20 From the foregoing, it is apparent that by the present invention there is provided an improved device for collecting and removing broken ends

in spinning and like machines, which device will function continuously without clogging of the suction passages by the broken ends.

I claim:

1. A device for collecting and removing broken ends in spinning and like machines, comprising in combination a collecting conduit extending longitudinally of the machine, said conduit being closed at one end and being connected to a source of suction at its other end, with said conduit being of varying cross section always increasing from said closed end to said suction end, and a series of suction heads projecting at intervals from said conduit and each providing hollow portions extending parallel to said conduit, having spaced openings into which broken ends from the machine are adapted to be individually drawn towards said source of suction, with said portions of the suction heads each being of varying cross section throughout, increasing in area in the di-

rection of movement of broken ends through said openings toward said suction source.

2. A device for collecting and removing broken ends in spinning and like machines, comprising in combination a collecting conduit extending longitudinally of the machine, said conduit being closed at one end and being connected to a source of suction at its other end, with said conduit being of varying cross section always increasing from said closed end to said suction end, and a series of hollow suction heads projecting at intervals from said conduit each providing spaced openings into which broken ends from the machine are adapted to be individually drawn, with said openings increasing in size along said heads in a direction away from said suction source, and with the cross section of each head increasing in the direction of movement of broken ends through said openings toward said suction source.
